UNITED STATES PATENT OFFICE.

LIONEL FITZ H. CAREW, OF NEW ROCHELLE, NEW YORK.

POWER-OPERATED CLEANING BRUSH.

Application filed January 16, 1926. Serial No. 81,720.

This invention relates broadly to new and useful improvements in power-operated brushes and has more specific reference to a water-operated rotary brush.

5 An important object of the present invention is the provision of a rotary brush adapted to be associated with a water motor of any ordinary or preferred construction, so that the water used to operate the motor 10 will also be utilized by the brush.

Another object of the present invention is the provision of new and novel means for connecting the brush with the motor, in such a manner that as the water exhausts from 15 the motor, it will pass through the brush and onto the object being cleaned.

Another object of the invention is to provide simplified means for transmitting the 20 rotary movement from the driving shaft of the motor to the brush.

Another object is to provide such a brush having associated therewith means for carrying a quantity of soap or the like which is 25 adapted to be used during the cleaning operation.

A further object of the invention is the provision of new and novel means for mounting the soap carrying means within the brush proper so that the exhaust water 30 from the motor will come in contact with the soap as it passes through the brush onto the object being washed.

A still further object is to provide a rotary brush of the character stated which 35 will save both time and labor in the cleaning of various objects such as the under surfaces of automobile fenders.

A still further object is to provide such a rotary brush which while simple in its construction, is nevertheless strong, sturdy and durable, practical and efficient in its operation and an advance in the art.

With these and numerous other objects in view, the invention resides in the novel construction, combination and arrangement of parts to be more fully hereinafter described, illustrated in the accompanying drawings and more particularly pointed out in the appended claims.

40 In the drawings forming a part of this application and wherein similar characters of reference denote corresponding parts throughout the several views:

Figure 1 is a front view of a power-oper-

ated brush constructed in accordance with 55 the present invention,

Figure 2 is a side elevation thereof,
Figure 3 is a sectional view substantially 60 on line 3—3 of Figure 1,

Figure 4 is a transverse sectional view on line 4—4 of Figure 3,

Figure 5 is a detail view of a slight modification of the present invention showing an additional way in which a hose may be secured to the water inlet port, 65

Figure 6 is a sectional view on line 6—6 of Figure 5.

Referring more particularly to the accompanying drawings and more especially to Figures 1 to 4 inclusive, wherein for the purpose of illustration has been disclosed a preferred embodiment of the present invention, the letter A denotes as a whole, a water motor which may be of any ordinary or preferred construction and in connection with 70 which the improved rotary brush B is adapted to be associated.

75 While, as stated above, the motor A may be of any ordinary or preferred construction, the type disclosed herein comprises a substantially circular housing 10 from one point of which extends the water inlet port 11 to which is adapted to be secured one end of a suitable water conductor such as a hose or the like, the other end of which may be secured to a suitable source of supply.

80 Formed on the periphery of the housing and extending in an opposite direction to the water inlet port 11, is the water outlet port 12 having secured thereto one end of 85 the tubular coupling 13 provided at its opposite end with the bearing sleeve 14 arranged in substantially parallel relation to the water outlet port 12.

85 Mounted transversely within the housing 10 is the usual drive shaft 15 projecting beyond the housing at one side thereof and having fixed thereto the worm gear 16 adapted to remain in constant mesh with the gear 17 positioned at right angles thereto and 90 fixed on the adjacent end of the shaft 18, the outer end portion of said shaft passing through the said bearing sleeve 14. It will, 95 of course, be understood that there is mounted on the shaft 15 within the housing 10, a plurality of vanes, propeller blades or the like so that the water engaging therewith will 100 cause the rotation of the said shaft which 105

will be imparted through the gears 16 and 17 to the shaft 18. It is not thought necessary, however, to disclose the construction within the housing inasmuch as it may be of 5 any ordinary or preferred type.

Upon reference to Figure 3, it will be clearly seen that the upper end portion of the shaft 18 is formed with the longitudinally disposed elongated recess 19 and that also 10 formed in the periphery of the shaft and communicating with the recess are a plurality of openings 20, positioned directly opposite the opening in the tubular coupling 13 and adapted for selective registration therewith as the shaft is rotated, whereby to effect 15 communication between the motor and the brush.

The brush B comprises in its construction a plurality of spaced inverted substantially 20 U-shaped wire ribs 21 carrying the bristles 22 secured thereto in any desired manner such as by twisting the wires constituting the ribs around the bristles as disclosed in the drawings. The free ends of the ribs are 25 suitably secured to the annular band 23 which in turn is bolted, as at 24, to the annular flange 25 formed on the periphery of the shaft 18 adjacent its outer end, said flange adapted to abut the enlarged end portion 30 of the bearing sleeve 14.

Arranged to be supported within the brush B is an elongated soap container or cage C extending longitudinally thereof, said container being preferably constructed 35 of wire and comprising the four substantially parallel corner wires 27 and the intermediate longitudinal side wires 28, these wires being connected by the inter-woven transverse wires 29. Carried by each of the 40 corner wires adjacent its opposite ends are the wire hooks or clips 30, the free ends of which engage the ribs of the brush as indicated at 31 whereby to securely retain the container in its proper position within the 45 brush.

This container is adapted to carry a quantity of soap or the like and secured to the end thereof adjacent the motor is a conical-shaped deflector 32 provided to spread the 50 water as it enters the brush.

In the operation of the invention, it will readily be seen that as the water enters the housing and through suitable means contained therein causes the rotation of the 55 shaft 15, this rotary movement will be transmitted to the shaft 18 through the worm gears 16 and 17 and inasmuch as the brush is secured to the flange of the shaft, the same will also be caused to rotate. As the 60 exhaust water passes out of the housing through the outlet port, it will be conducted through the tubular coupling 13, and thence into the brush through the spaced openings 20 and the recess 19 in the said shaft 18. 65 The water engaging with the deflector 32

will be spread in all directions and as the brush continues to rotate, this water will run over and come into contact with the soap or the like within the wire cage C before it passes through the wire ribs of the brush 70 onto the object being cleaned. In this manner, the water as it comes into contact with the object being cleaned will have mixed therewith a quantity of soap whereby to effect the easy cleaning of the object. 75

In Figures 5 and 6 has been shown another way in which a hose may be secured to the water inlet port of the motor and by reference to these figures, it will be noted that there is provided the motor A comprising a circular housing 10, provided with the water inlet port 11. However, in this form, there is secured to the water inlet port 11, in any suitable manner, such as by means of the bolt 32, a bracket 33 to the outer end 85 of which is secured the bight portion 34 of the clamp 35 having the arcuately curved resilient arms 36 and 37, the free ends of which are provided with the lugs 38 and 39 through which pass the bolt 40 having 90 threaded upon one end thereof a wing nut or the like 41, the portion of the bolt intermediate the said lugs 38 and 39 being encircled by the coil spring 42 which acts to normally urge the spring arms 36 and 37 95 apart.

The numeral 43 denotes one end of a suitable hose, the other end of which may be attached to the source of water supply in any desired manner. In the application of 10 the clamp, the wing nut 41 is first loosened so that the spring arms will be forced apart by the action of the spring 42 to a degree sufficient to permit the insertion of the hose between the same and the water inlet port, 10 it being of course understood that the hose is slipped over the said inlet port. The wing nut 41 is then subsequently tightened whereupon the spring arms 36 and 37 of the clamp 35 will engage the hose 43 and clamp 11 the same tightly onto the water inlet port 11.

From the above, it will be readily appreciated that there has been provided a new and novel water-operated rotary brush which will accomplish all of the objects and perform all of the functions claimed hereinabove. Also, that while there has been illustrated and described a preferred embodiment thereof, it is to be understood, that various changes or modifications in the details of construction may be resorted to without departing from or sacrificing the spirit of the invention so long as these modifications or changes fall within the scope of the appended claims.

What is claimed is:

1. A brush head structure designed to have water forced into the interior thereof, comprising a base plate, having a passage therethrough for the extension therethrough 1

of a discharge end of a water pipe and a plurality of inverted substantially **U**-shaped frames having the free ends of their legs secured at diametrically opposite points in said plate, and bristle elements secured to and projecting outwardly from said frames throughout the length of the same.

2. In combination, a brush head structure adapted to be revolvably mounted upon a water discharge element, comprising an annular plate body adapted to be secured to said element, a plurality of inverted substantially **U**-shaped frames extending outwardly from one face of said plate and having the free ends of their legs secured at diametrically opposite points in the plate, bristle members secured to and projecting outwardly from each of said frames, and a foraminous soap receptacle adapted to be mounted within said head, said receptacle having an imperforate bottom of conical shape designed to be arranged over said water dis-

charge element to cause water to be spread laterally within the head.

3. In combination, a brush head structure adapted to be revolvably mounted upon a water discharge element, comprising a base plate body designed to be secured to said element, a plurality of inverted substantially **U**-shaped frames, extending outwardly from the face of said plate and having the free ends of their legs secured at diametrically opposite points in the plate, bristle members secured to and projecting outwardly from each of said frames, a wire soap cage structure arranged within said head, and a plurality of clip members extending from the wall of said cage to and engaging said frame legs to suspend said cage in position within the head.

In testimony whereof I affix my signature.

LIONEL FITZ H. CAREW.
